UNITED STATES PATENT OFFICE.

COURTLAND B. MEUSER AND JOHN G. BREITHAUPT, OF ASHLAND, OHIO.

LOCKING ELECTRICAL SWITCH.

1,233,098.

Specification of Letters Patent. Patented July 10, 1917.

Application filed April 17, 1916. Serial No. 91,744.

To all whom it may concern:

Be it known that we, COURTLAND B. MEUSER and JOHN G. BREITHAUPT, citizens of the United States, residing at Ashland,

5 in the county of Ashland and State of Ohio, have invented certain new and useful Improvements in Locking Electrical Switches, of which the following is a specification.

10 This invention relates to electrical switches, and has special reference to an improvement in that type thereof wherein the switch lever may be locked against movement.

15 To this end, the invention contemplates an electrical switch device including a lever that may be readily and quickly locked in its open position to prevent unauthorized persons operating the switch to close the 20 circuit controlled thereby. Thus, the invention is of special utility in connection with switches that have to be located in places where unauthorized persons are likely to tamper therewith, as for instance, 25 automobiles or other vehicles using an electrical current.

Accordingly, the present invention has primarily in view a novel and practical switch locking device of the character indicated which is simple and reliable in operation, and easily locked without the use of 30 separate locks or keys. That is to say, the present invention contemplates a switch device including a lock of the keyless or 35 permutation type, thus making the switch inoperative to all except authorized parties familiar with the proper combination.

With the above and other objects in view 40 which will more readily appear as the nature of the invention is better understood, the same consists in the novel construction, combination, and arrangement of parts hereinafter more fully described, 45 illustrated and claimed.

50 A preferred and practical embodiment of the invention is illustrated in the accompanying drawings, in which—

Figure 1 is a front elevation of the present invention showing the switch lever in 55 its normal locked position.

Fig. 2 is a vertical sectional view on the line 2—2 of Fig. 1.

Fig. 3 is a view similar to Fig. 1 showing the switch lever unlocked and in one of its 60 two circuit closing positions.

Fig. 4 is a vertical sectional view on the

line 4—4 of Fig. 3 showing more clearly the relation of parts when the switch lever is unlocked as shown in Fig. 3.

Fig. 5 is a cross sectional view on the line 5—5 of Fig. 3.

Similar reference characters designate corresponding parts throughout the several figures of the drawings.

Although the present invention is susceptible of application to various types of electrical switches, it is of special utility in connection with those commonly found on automobiles, and accordingly, there is shown in the drawings, for the purpose of illustration, a switch construction of the type especially designed for use in connection with a dual ignition system which requires a two-position switch. Therefore, in carrying the present invention into effect, 75 it is proposed to employ a switch base member 1 having fastening receiving openings 2 for facilitating the attaching of the device to a support, and also having a switch cover 3 which provides a housing for the 80 switch mechanism and locking devices constituting the present invention.

As will be apparent from an inspection of the drawings, the switch cover 3 is provided in its front wall with a switching slot 85 4 which is of substantially T-shaped form. That is to say, this slot essentially includes a tail portion T having at one end the laterally disposed wing portions W, in which a main switch lever 5 is adapted to move. 90 This switch lever is preferably of angular formation as will be observed more particularly from Figs. 2 and 4, and therefore includes a handle portion H which is adapted to project exteriorly of the switch cover to 95 be accessible to the operator, and an internal shank portion S having a reduced upper end 6 which is swiveled in a sleeve member 7 pivotally mounted between the spaced posts 8 rigidly carried by the base member 1. Thus, the switching lever 5 has a swivel mounting pivotally supported on the switch base whereby it may have both a swinging movement between the posts 8, and a lateral movement because of the 100 swivel connection at the shank end thereof with the sleeve 7, whereby the handle portion H of the lever may freely move from the tail portion of the slot 4 into the wings thereof as will hereinafter more fully appear.

With further reference to the switch lever

5, it will be observed that the same rigidly carries on its shank portion 8 adjacent the angular handle portion 11, a transversely disposed bar of insulating material 9 having at the ends thereof contact members 10 to which are attached the terminals of current carrying wires 11. Mounted on the switch base 1 directly behind the ends of the insulating bar 9 which carries the terminals 10 of the circuit wires, are fixed contacts 12, so that when the switch lever is pushed into either one of its two circuit closing positions, the electrical circuit will be closed through the contacting of one of the movable wire terminals with one of the fixed contacts 12. For the purpose of maintaining the switch lever in its normal open position, that is, so that the terminal contacts carried by the bar 9 are clear of the contacts 12, a spring 13 is employed, the same having one end attached to the shank of the lever and the other end anchored to the switch cover. Therefore, under ordinary conditions, it will be clear that the tension of the spring 13 will draw the handle portion of the switch lever upwardly into the tail portion T of the switching slot 4, and thus hold the switch parts in their open position as above indicated.

In order to lock the switch lever 5 in the tail portion of the slot 4, a permutating locking device D may be employed. This device is supported between the cover plate 3 and base member 1 in a position directly below the switch lever. As will be observed from the drawings, this locking device essentially includes in its organization a plurality of permutating disks or tumblers 14, 15, and 16 carried upon the spindle 17 of an operating knob 18 disposed exteriorly of the cover. The spindle of this operating knob above referred to is provided with a squared portion 19 for receiving the master disk 14, while the remainder of the spindle is formed round as indicated at 20 and carries the secondary permutating disks 15 and 16, which are spaced from the master disk, each other, and the base of the casing by means of the suitable spacing washers 21. The end of this spindle opposite the knob 18 receives a nut 20* which rotatably locks the spindle to the base.

The said permutating disks or tumblers 14, 15, and 16 are each provided with serrated peripheries as shown, although this is not essential for the master disk 14, since the latter is provided with a hub ratchet 14^a for engaging with a spring pawl 14^b which constitutes a friction brake or drag for this disk, and to provide a similar braking effect on each of the other disks, a double fingered spring 22 is employed, as shown. In order that the master disk may pick up the adjacent disk 15 of the series, and the latter, in turn, pick up the succeeding one, each disk is provided with offset lugs or projec-

tions 23. Accordingly, it will be apparent that upon turning the operating knob 18, the master disk 14 will be the first to rotate and will pick up the disk 15, which latter will, upon further manipulation of the knob 18 in the proper direction, pick up the disk 16 to thereby bring the switch lever clearance notches 24 of each disk into alignment with the lower end of the tail portion of the switching slot 4. The switch lever 5 may then be moved through the aligned clearance notches from its position in the tail portion of the notch by downward hand pressure upon the handle portion thereof, to be shifted into either of the wings of the switching slot.

All of the permutating disks of the locking device D, are arranged in close proximity to the switch lever 5, so that the peripheries thereof are substantially in line with a horizontal plane at the lower or exit end of the tail portion of the slot. Thus, when the switch lever is held by the spring 13 in its normal position in the tail portion T of the slot 4, the peripheries of the disks 14, 15, and 16 will prevent the swinging downward of the lever on its pivotal support between the posts 8, when hand pressure is supplied to the end of the handle H. Therefore, in order for the circuit to be closed by the lateral turning of the main switch lever 5, it will be clear that all of the clearance notches 24 in the disks 14, 15, and 16 must be in alignment, and they can only be brought into alignment by authorized parties knowing the correct number of turns in different directions to give the knob 18. In connection with this feature of the invention, it is important to note that all of the disks must be in such a position that the notch in each one thereof is in alignment, or it will be impossible to close the circuit through the lateral shifting of the switch lever, since it is essential for the switch lever to make a full downward swing before it can be shifted past the restraining shoulders 25 on each side of the exit end of the tail portion T of the slot to enter the oppositely disposed keeper notch portions 26 of the wings. That is to say, the switch lever is only movable to either one of the two operative positions when engaged with the disks of the locking device.

From the foregoing, it will be apparent that the present device essentially comprises a switch lever 5 which has both a swinging movement about its point of pivotal support, and a lateral movement at right angles to the swinging movement, thus especially adapting the lever to follow the path of a substantially T-shaped switching slot to obtain a two-way circuit closing position and an intermediate locking position. That is to say, owing to the swivel connection of the shank end of the switch lever with the sleeve 130

7, which is pivotally supported between the posts 8, it is possible to move the angular switch lever downwardly in the tail portion of the slot against the tension of the spring 13, unless the swinging movement is prevented by the disks of the locking device D, in which case, the switch is locked. However, on the other hand, if the clearance notches 24 of the disks of the locking device 10 are in alinement, the downward swinging of the switch lever 5 may be accomplished without hindrance, so that the handle portion H thereof may be shifted to either one side or the other into the laterally disposed 15 wings W of the slot, whereby the tension of the spring 13 will pull the handle into one of the keeper notches 26 upon the release of hand pressure on the handle. Thus, the contact is made on whichever one of the 20 contacts that the operator desires, according to the lateral direction in which the handle of the switch is shifted. When it is desired to bring the switch lever back to its normal position in the tail portion T of the slot 4, it is only necessary to release the same from 25 the keeper notch 26 and bring it back into alinement with the said tail portion of the slot. Upon releasing the handle in this position, the spring 13 pulls the same into the 30 slot so that it is locked against movement in a lateral direction, and then the knob 18 of the locking device is turned so that the notches in the permutating disks are out of alinement and the peripheries of the latter 35 come into obstructing relation with respect to the path of movement of the elbow portion of the switch lever. In this position of parts, the circuit is broken, and the switch is locked in its open position.

40 Without further description, it is thought that the many features and advantages of the present invention will be readily apparent, and it will also be understood that various changes in the form, proportion, 45 and minor details of construction may be resorted to without departing from the spirit of the invention or scope of the appended claims.

I claim:

50 1. A locking electrical switch including a switch cover having a slot comprising a tail portion and laterally disposed wing portions, a spring tensioned switch lever having a swinging movement and also a lateral pivotal movement and normally resting in the tail portion of said slot, and locking means 55 for preventing the exit of the switch lever from the tail portion of the slot.

60 2. A locking electrical switch including a switch cover having a slot comprising a tail portion and laterally disposed wing portions, a spring tensioned switch lever having a swinging movement and also a lateral pivotal movement and normally resting in the 65 tail portion of said slot, and permutation

lock means for preventing the exit of the switch lever from the tail portion of the slot.

3. A locking electrical switch including a switch cover having a slot comprising a tail portion and laterally disposed wing portions, a spring tensioned switch lever having a swinging movement and also a lateral pivotal movement and normally resting in the tail portion of said slot, and permutation 70 lock means including a plurality of permutating disks for preventing the exit of the switch lever from the tail portion of the slot. 75

4. A locking electrical switch including a switch cover having a slot comprising a tail portion and laterally disposed wing portions, a spring tensioned switch lever having a swinging movement and also a lateral pivotal movement and normally resting in the tail portion of said slot, and permutation 80 lock means including a plurality of permutating disks having peripheral notches normally out of registry to prevent the exit of the switch lever from the tail portion of the slot. 85

5. A locking electrical switch including a switch cover having a slot comprising a tail portion and laterally disposed wing portions, a spring tensioned switch lever having a swinging movement and also a lateral pivotal movement and normally resting in the tail portion of said slot, and permutation 90 lock means coöperating with the tail portion of said slot and including a plurality of permutating disks each having a lever 95 clearance notch in its periphery and mounted on an operating spindle, said disks adapted to be rotated by the spindle to bring the notches in registry to release the lever from the tail portion of said slot. 100

6. A locking electrical switch including a switch cover having a slot comprising a tail portion and laterally disposed wing portions, a spring tensioned switch lever having a swinging movement and also a lateral movement, and notched permutating disks adapted to be brought into registry to permit the switch lever to move from its normal position in the tail portion of the slot laterally into either wing thereof. 115

7. A locking electrical switch including a switch base carrying fixed contacts, a cover member having a slot including a tail portion and laterally disposed wings, a spring tensioned switch lever having a swivel 120 mounting pivotally supported on said switch base, whereby said lever has both a swinging movement and also a lateral movement, separate wire terminal contacts carried by said lever, and means for locking the switch lever in the tail portion of said slot. 125

8. A locking electrical switch including a switch base carrying fixed contact, a cover member having a slot including a tail portion and laterally disposed wings, an angu- 130

lar spring tensioned switch lever having a swivel mounting pivotally supported on said switch base whereby said lever has both a swinging movement and also a lateral movement and separate wire terminal contacts carried by said switch lever, and locking means for holding switch lever in the tail portion of said slot.

9. A locking electrical switch including a switch base carrying fixed contacts, a cover member having a slot including a tail portion and laterally disposed wings, an angular switch lever having a swivel mounting pivotally supported on said switch base whereby said lever has both a swinging movement and also a lateral movement, a spring for drawing the switch lever in the direction of the tail portion of said slot, separate wire terminal contacts carried by said lever, and means for locking the lever in the tail portion of said slot.

10. A locking electrical switch including a switch base carrying fixed contacts, a cover member having a slot including a tail portion and laterally disposed wings, a switch lever having a swivel mounting pivotally supported on said switch base whereby said lever has both a swinging movement and also a lateral movement, oppositely located

wire contacts carried by said lever, a spring 30 for normally maintaining the terminal contacts carried by the switch lever out of contact with the fixed contacts on the base and in the tail portion of said slot, and means for locking the lever in the said tail portion 35 of the slot.

11. A locking electrical switch including a switch base carrying fixed contacts, a switch cover having a slot, a spring tensioned switch lever having a swivel mounting pivoted to said base whereby said lever has both a swinging movement and also a lateral movement, said base also carrying separate wire terminal contacts, said lever being adapted to work in said slot, and means 40 movable into and out of the path of movement of said lever to either lock the same in the slot or permit its movement toward the fixed contacts.

In testimony whereof we hereunto affix 45 our signatures in the presence of two witnesses.
